8 Claims. (Cl. 37—108)

1

This invention relates to an excavating device and more particularly to an excavating device which is adapted to prepare the sub-grade for an additional strip of pavement to be added to an already existing roadway.

With the increase in the number and size of motor vehicles using the highways, it has become a common practice in many areas to add a relatively narrow strip of surfacing material to existing roads of insufficient width in order to provide a roadway which is more suitable for type of use to which it is now subjected. Concrete, bituminous concrete, crushed stone, or a variety of other materials may be utilized for this purpose.

Various methods of excavating the earth immediately adjacent the road to be widened to provide for the added strip of surfacing material have been tried, including the use of the conventional type of motor grader, which, however, is ill adapted for this type of work. Mechanical ditch digging equipment of the bucket-chain type have also been used. Even when such mechanical equipment is used, it is normally necessary to perform a substantial amount of the work by hand labor in order to attain a satisfactory sub-grade for the additional strip of road surface material.

When a motor grader is utilized for excavating the shoulder material, it is normally necessary to move the grader so that the wheels on one side thereof ride on the surface of the existing road and the wheels on the opposite side ride on the shoulder. This in itself causes a great amount of difficulty since it is almost impossible under such conditions to make a cut having a level bottom and of the desired depth. Since the specifications for such a widening strip normally call for a particular depth of surfacing material in the added strip, it is highly desirable to form the cut for the widening strip so that it has as nearly uniform a depth as possible, exactly equal to the depth called for in the specifications. Obviously if the sub-grade in the cut is made deeper than the depth of surfacing material called for, it will be necessary to use additional surfacing material to bring the surface of the widening strip up to the level of the surface of the existing road. This, of course, is a very costly procedure and it is therefore highly desirable to have the sub-grade formed originally as accurately as possible. Likewise, if the level of the sub-grade in the excavation is too high, the widening strip will not be of sufficient depth to meet the specifications normally set up for such an operation.

2

The present device is particularly useful in connection with the widening of concrete roads or other roads having a well-defined lateral edge. In widening such a highway, it is a general practice to remove a strip of the contiguous earth or other material from the shoulder to the desired depth which may be equal to the depth of the concrete in the existing roadway, and to then deposit in the excavated strip a sufficient amount of surfacing material to form a surface which is substantially level with the surface of the existing road. Preferably, when the added strip is formed of concrete, a self-powered pouring mechanism is utilized which may carry with it, as an integral part thereof, a vertically disposed form, which form is adapted to initially contain the freshly poured concrete. This form moves with the pouring mechanism and a portion of the previously excavated earth is continually packed against it so that as the form moves out of association with the freshly poured concrete, the earth so packed serves to retain the lateral edge of the newly poured material. This alleviates the necessity for using wooden forms or the like to form the lateral edge of the widening strip and permits the outer edge of the excavation to have a relatively rough contour, as long as the excavation is made slightly wider than the desired width of the widening strip to be added.

It is, therefore, an object of this invention to provide a self-powered excavating device which is adapted to ride entirely on the upper surface of the existing road to be widened, and which therefore obtains its vertical alignment from that surface.

Likewise, it is an object of this invention to provide such an excavating device which is adapted to be laterally aligned when in operation with the lateral edge or surface of the existing slab, which result is achieved by having the device so constructed as to also bear against the vertical edge of the existing road, as well as the upper surface thereof.

Another object of this invention is to provide an excavating device which will make a cut of the desired width and depth along the side of an existing concrete or other similar roadway and which will dispose all of the earth or other material removed from the cut in a suitable windrow along the outer edge of the cut.

Still another object of this invention is to provide a device of the character described which produces a satisfactory sub-grade for the widening strip in a minimum number of passes; which is capable of preparing a cut or excavation having a substantially constant depth; and which

removes substantially only that amount of earth in a lateral direction or other material necessary to permit the widening strip to be poured.

Yet another object of this invention is to provide an excavating device of the character described which may take the form of a special piece of self-powered equipment or of an attachment for the conventional type or motor grader which can be very quickly attached to or removed from association with the grader.

Another object of this invention is therefore to enable the conventional motor grader to be utilized both in the usual fashion for the ordinary type of work performed by it, and also as the supporting and driving mechanism for an excavating device of the character described, so that only one operator is required for the operation of both the grader and the excavating device.

Still another object of this invention is to provide an excavating device of the character described which is relatively simple in construction and operation and therefore relatively inexpensive to produce and yet which results in a tremendous saving of time, labor and materials in the operation of widening an existing roadway, in the manner described.

With these and various other objects in view, the invention consists of certain novel features of construction as will be more fully described and particularly pointed out in the specification, drawings and claims appended hereto.

In the drawings:

Figure 1 is a view in elevation of one form of excavating device embodying the present invention, the device being in the form of an excavating attachment secured to a motor grader and being shown in the normal operating position with relation to an existing roadway;

Figure 2 is a plan view from above of the detachable excavating attachment shown in Figure 1, with the blade of the motor grader being shown in horizontal section;

Figure 3 is a view in elevation and partly in vertical section of the excavating attachment shown in Figure 1, the view being taken from the rear of that portion of the device;

Figure 4 is a view in vertical section of a portion of the excavating attachment and the blade of the motor grader shown in Figures 1 and 2, the view being taken along the line 4-4 of Figure 2.

Referring now to Figure 1, the excavating device shown therein is in the form of a conventional motor grader 10 having removably secured thereto the excavating attachment, indicated generally by the numeral 12. This latter attachment is adapted to be secured to the blade 14 of the motor grader which blade is shown in Figure 2 in horizontal section, and in Figure 4 in vertical section.

The excavating or plow attachment 12 is provided with a main beam 16 which may be in the form of a steel I-beam, as best shown in Figure 4. This beam 16 has secured thereto a plurality of metal blocks 18, 20, 22 and 24 welded or otherwise attached thereto which may be disposed in spaced relation along the upper surface of the I-beam 16 abutting the flange 26 on one side of the beam 16. The sides of these blocks which are opposite the flange 26 may be given an angular disposition which adapts them to snugly receive the lower edge 28 of the blade 14 as best shown in Figure 4. The blade 14 may have a plurality of securing members, such as the lugs 30, 31 and

32, secured adjacent the upper edge thereof which, in turn, are adapted to receive fastening members threaded at one end, such as the pins 34 and 36, and which are secured at the opposite end to flexible members, such as the chains 38, 39 and 40. These chains may have their lower ends fastened to securing members on the beam 16, such as the lugs 42, 43, 44 and 45. This provides for a convenient method of firmly securing the plow attachment 12 to the blade 14 but also readily permits it to be detached when desired. The threaded pins 34 and 36, for example, may be inserted through the lugs 30 and 32, respectively, and the chains 38 and 40 drawn up tightly by tightening the nuts 46 and 48 on the pins 34 and 36, respectively, as shown in Figure 4.

The beam 16 may also be provided with a roller 50 at its outer extremity 52, which extremity may be given an appropriate configuration so that the axis of rotation of the roller 50 may be disposed at a suitable angle to the longitudinal axis of the beam 16, as shown in Figure 2.

The inner end of the beam 16 has secured thereto a metal frame structure lying in substantially the same plane as the beam 16. This frame structure is formed of the main arm 54 secured at one end to the beam 16 adjacent the block 18 and extending forwardly into association with the arm 56, which is also secured at one end to the main beam 16. The outer end of the arm 56 is secured to the frame member 58 which is disposed perpendicularly to the arm 54. The frame member 60 is also secured to the arm 56, at an intermediate point, and to the other end of the arm 54. The frame members 58 and 60 together with the members 62 and 64 form a supporting frame for the roller 66 which is similar to the roller 50 and has its axis of rotation disposed parallel to the axis of the roller 50. The frame members 68, 70, 72 and 74 likewise form a supporting frame for the roller 76 on the opposite side of the main beam 16, this latter roller also having its axis of rotation disposed parallel to the other two rollers 50 and 66.

The ends of the frame members 58 and 60 opposite to the ends to which the arm 56 is secured are also secured to a vertically disposed baffle plate 78 which is angularly disposed in turn with respect to the main beam 16, as best shown in Figure 2. This plate 78 is comparable in some respects to the share of a conventional plow and is adapted to shear the earth and other shoulder material from the lateral edge of the road slab as it is moved forward in association with that edge. It may be secured intermediate its ends to the beam 16 by welding, or other suitable means, and may have a gap 80 formed therein immediately above the beam 16 to permit the blade 14 of the motor grader to be more easily inserted in driving relation with the plow attachment 12. The rear portion of the baffle plate 78 is likewise secured to one end of the frame member 68 and is also secured to the frame member 72, both directly and by the triangular plates 82 and 84 disposed on the top of the frame member 72. The leading edge 86 of the baffle plate 78 may have secured thereto by welding, for example, a rub plate 88 formed of wear-resistant metal, which plate is adapted to bear against the lateral edge 90 of the road 92, as best shown in Figure 2 when the device is in operation.

As shown in Figures 2 and 3, the vertical baffle plate 78 may have a pair of rollers 94 and 96 mounted in spaced relation on the lower portion

thereof so that their axes of rotation are substantially perpendicular to the common plane of the main beam 16, and the associated frame members just described. As best shown in Figure 3, these rollers extend through suitable openings in the plate 78 and are adapted to bear against the lateral edge 90 of the existing road 92 when the excavating device is in the operating position. It may thus be seen that the main beam 16 and its associated frame work together with the vertical baffle plate 78 are capable of being moved along the edge 90 of the existing road 92 in continuous alignment therewith, both laterally and vertically, the vertical alignment being accomplished by the three rollers 50, 66 and 76, and the lateral alignment being accomplished by the rollers 94 and 96.

Attached to the frame work just described and the plate or share 78 is the moldboard 98 which is preferably disposed so that its longitudinal axis is substantially perpendicular to the longitudinal axis of the main beam 16. One lateral edge of the moldboard 98 is secured to the baffle plate or share 78 in front of the point at which the inner end of the beam 16 is attached to the moldboard, the lower edge of the moldboard extending substantially to the leading edge 86 of the baffle plate 78, as best shown in Figure 1. The outer edge 102 of the moldboard 98 has a projecting portion 104 formed thereon which insures that no loose dirt will roll back into the cut after the excavating attachment has passed. The contour of the moldboard 98 may be substantially the same as a conventional snowplow or the like which is adapted to throw up a windrow of material to one side thereof. The lower edge 106 thereof is disposed in a plane parallel to the common plane tangent to the bottom surface of the three rollers 50, 66 and 76, so that the base of the cut made by the plow will normally be parallel to the road surface upon which those three rollers rest. The lower edge 106 of the moldboard 98 is preferably of a length such that the distance between the outer extremity thereof and the vertical baffle plate 78, as shown in Figure 3, is slightly greater than the desired width of the widening strip being added to the existing road.

Of course, provision could be made for securing an extension to this outer edge of the moldboard to provide for the removal of strips of varying width.

The outer end of the frame member 72 is secured to the outer end of the moldboard 98, as best shown in Figures 2 and 3, and this end of the frame member 72 may be braced with the frame members 108 and 110, the latter in turn being secured to a frame member 112 extending between substantially the midpoint of the moldboard 98 and the vertical baffle plate 78. Additional support may be provided for the baffle plate 78 by the strut member 114 extending from the frame members 54 and 62 to the top of the baffle plate 78, substantially at the point where the top edge 116 of the moldboard 98 meets the baffle plate 78.

An angularly disposed ramp plate 118 may be provided immediately in front of the roller 66, having its upper edge secured to the frame member 58 and one of its lateral edges secured to the baffle plate 78 so that it extends downwardly toward the road 92 as shown in Figure 2. A similar ramp member 120 may be provided behind the roller 16 having its upper edge secured to the frame member 72 and one of its lateral

edges secured to the vertical baffle plate 78. These two ramp members 118 and 120 aid in moving the motor grader in proper position for securing of the excavating attachment to the 5 blade of the grader. The left-hand front wheel of the grader may be driven over the ramp member 120 and then over the frame work of the excavating attachment, and down the ramp member 118. This puts the motor grader in substantially the correct position for attachment of the 10 blade when the blade is disposed at the proper angle. Similar ramp members may be provided on the outer end of the main beam 16, if desired, in order to enable the right-hand front wheel of the motor grader to pass easily over the beam 16.

As previously described when the grader has been driven into a suitable position so that the excavating attachment is disposed as shown in Figure 1, the blade 14 may be secured in position on the main beam 16, as shown in Figure 4, and the whole device is then ready for operation. If the excavating operation is just beginning at a particular point, the excavating attachment 12 can be aligned with the edge of the road 90 and 25 as the motor grader is moved forward, gradually lowered, so that it digs into the shoulder of the road until the rollers 50, 66 and 76 are in contact with the surface of the road 92.

At the same time the motor grader is manipulated so that it tends to move forward at a slight angle toward the center of the road 92, which will cause the rub plate 88 and the rollers 84 and 96 on the vertical baffle plate 78 to be held in intimate contact with the lateral edge of the road 92. The blade of the motor grader may be so positioned, after the excavating attachment is secured thereto, so that the blade and the motor grader itself forces the beam 16 and its associated frame work downwardly and maintains the rollers 50, 66 and 76 in intimate relation with the upper surface of the road 92. The disposition of these rollers so as to form a triangle aids in insuring that any undesirable variations in the surface of the road 92 have a minimum amount of effect on the vertical alignment of the plow member 12.

In the embodiment of the invention shown, the main beam 16 is of a length such that the roller 50 rides on the center line 122 of the road 92. This has been found to be a desirable length, although, of course, this will depend upon the width of the existing road upon which the device is being operated. Obviously, the form of the frame work supporting the rollers 66 and 76 and the moldboard 98 need not be of the precise construction illustrated, although it has been found that the relative disposition of the main beam 16 and the moldboard 98 should be substantially that as shown, for best results. The angular disposition of the moldboard 98 and the main beam 16 relative to the share or baffle 78 may, of course, be varied somewhat but the angles shown in Figure 2 have been found to provide satisfactory operation.

As previously mentioned, although the device which has been primarily described in this specification is in the form of a motor grader having a detachable excavating portion associated therewith, applicants do not wish to limit themselves to this detachable form. Obviously a device in which the excavating portion is formed integrally with the remainder of the mechanism is also within the confines of this invention.

It is, therefore, to be understood that the invention is not to be limited by the exact embodiment.

ments of the device shown, which are merely by way of illustration and not limitation, as various other forms of the device will, of course, be apparent to those skilled in the art without departing from the spirit or scope of the invention as defined in the following claims.

We claim:

1. An excavating device adapted to remove a strip of shoulder material from association with the lateral edge of an existing road slab, comprising a self-propelled vehicle, a freely adjustable supporting and driving frame carried by said vehicle, a horizontally disposed alignment member secured to said supporting and driving frame adapted to be moved with said vehicle so as to be held in intimate contact with the upper surface of said road slab and to be supported thereby, a vertically disposed alignment and cutting element secured to and supported by said horizontal alignment member adapted to be held in intimate contact with one of the sides of said road slab when said horizontal alignment member is moved with said vehicle and a moldboard angularly secured to said vertical alignment and cutting element and to said horizontal alignment member and supported by the latter member, the vertical and lateral disposition of said moldboard being thus determined by the disposition of the upper surface and the side of said road slab, respectively.

2. An excavating device adapted to remove a strip of shoulder material from association with the lateral edge of an existing road slab, comprising a self-propelled vehicle, a freely adjustable supporting and driving frame carried by said vehicle, a horizontally disposed alignment member secured to said supporting and driving frame, a plurality of spaced rollers on the horizontal alignment member adapted to be held by said vehicle in rolling contact with the upper surface of said road slab so that said alignment member is supported by said road slab, a vertically disposed alignment and cutting element secured to and supported by said horizontal alignment member, a plurality of spaced rollers on said vertical alignment and cutting element adapted to be held by said vehicle in rolling contact with one of the sides of said road slab, and a moldboard angularly secured to said vertical alignment and cutting element and to said horizontal alignment member and supported by the latter member, the vertical and lateral disposition of said moldboard being thus determined by the disposition of the upper surface and the side of said road slab, respectively.

3. In an excavating device adapted to remove a strip of shoulder material from association with the lateral edge of an existing road slab, a plow member comprising a horizontally disposed alignment member adapted to be moved by a self-propelled vehicle along said road slab in intimate contact with the upper surface thereof so as to be supported by said surface, a vertically disposed alignment and cutting element secured to and supported by said horizontal alignment member adapted to be held in intimate contact with one of the sides of said road slab when said horizontal alignment member is moved by said vehicle, and a moldboard angularly secured to said vertical alignment and cutting element and to said horizontal alignment member so as to be supported by the latter member, the vertical and lateral disposition of said moldboard being thus determined by the disposition of the upper surface and the side of said road slab, respectively.

4. An excavating attachment for a self-pro-

pelled road grader having an adjustable blade, which attachment is adapted to remove a strip of shoulder material from association with the lateral edge of an existing road slab comprising a horizontally disposed alignment member adapted to be removably secured to the blade of said road grader so that it may be held in intimate contact with the upper surface of said road slab and be supported thereby as said grader is moved thereon, a vertically disposed alignment and cutting element secured to and supported by said horizontal alignment member adapted to be held in intimate contact with one of the sides of said road slab when said horizontal alignment member is moved with said road grader, and a moldboard angularly secured to said vertical alignment and cutting element and to said horizontal alignment member so as to be supported by the latter member, the vertical lateral disposition of said moldboard being thus determined by the disposition of the upper surface and the side of said road slab, respectively.

5. An excavating attachment for a self-propelled road grader having an adjustable blade, which attachment is adapted to remove a strip of shoulder material from association with the lateral edge of an existing road slab, comprising a normally horizontal alignment member adapted to be removably secured to the blade of said road grader, a plurality of rotatable members on said alignment member adapted to be held in intimate contact with the upper surface of said road slab when said attachment is in the excavating position and adapted to support a part of the weight of said road grader when said adjustable blade is lowered below the position of normal abutment with said alignment member when the latter is supported by said road slab, a vertically disposed alignment and cutting element secured to and supported by said horizontal alignment member adapted to be held in intimate contact with one of the sides of said road slab when said horizontal alignment member is moved by said road grader, and a moldboard angularly secured to said vertical alignment and cutting element and to said horizontal alignment member so as to be supported by the latter member, the vertical and lateral disposition of said moldboard being thus determined by the disposition of the upper surface and the side of said road slab, respectively.

6. An excavating attachment for a self-propelled road grader having an adjustable blade, which attachment is adapted to remove a strip of shoulder material from association with the lateral edge of an existing road slab, comprising a guide member adapted to be removably secured to the blade of said road grader so that it may be held in intimate contact with the upper surface and one of the sides of said road slab as said grader is moved thereon, a horizontal alignment member forming a part of said guide member adapted to be moved in contact with the upper surface of said road slab, a vertically disposed alignment member forming a part of said guide member adapted to be moved in contact with said side of said road slab, a cutting blade secured to the leading edge of said vertically disposed alignment member adapted to normally abut said side of said road slab and a moldboard angularly secured to said vertical alignment member and to said horizontal alignment member so as to be supported by the latter member, the vertical and lateral disposition of said moldboard being thus determined by the

disposition of the upper surface and the side of said road slab, respectively.

7. An excavating attachment for a self-propelled road grader having an adjustable blade, which attachment is adapted to remove a strip of shoulder material from association with the lateral edge of an existing road slab, comprising a horizontally disposed alignment member adapted to be moved in intimate contact with the upper surface of said road slab as said grader is moved thereon, a blade receiving element angularly disposed to the longitudinal axis of said alignment member, means for removably securing said adjustable blade on said road grader to said blade receiving element, a vertically disposed alignment member secured to and supported by said horizontal alignment member adapted to be moved in intimate contact with one of the sides of said road slab when said horizontal alignment member is moved with said road grader, a cutting element secured to the leading edge of said vertically disposed alignment member adapted to be held in sliding contact with said side of said road slab when said vertically disposed alignment member is moved in contact therewith, a moldboard angularly secured to said vertical alignment member and to said horizontal alignment member substantially at right angles to said blade receiving element and supporting means for said moldboard secured to said horizontal alignment member, the vertical and lateral disposition of said moldboard being thus determined by the disposition of the upper surface and the side of said road slab, respectively.

8. An excavating attachment for a self-propelled road grader having an adjustable blade, which attachment is adapted to move a strip of shoulder material from association with the lateral edge of an existing road slab, comprising a guide member, a plurality of rotatable members on said guide member adapted to be moved in contact with the upper surface of said road

slab and one of the sides of said slab, a blade receiving element angularly disposed to the longitudinal axis of said guide member, means for securing said blade to said blade receiving element so that when said blade is lowered sufficiently a portion of the weight of said road grader is carried by said rotatable members, a vertically disposed alignment member forming a part of said guide member, which vertically disposed alignment member is adapted to move in intimate contact with said side of said road slab, a cutting element secured to the leading edge of said vertically disposed alignment member adapted to move in sliding relation with said side of said road slab when said attachment is moved with said road grader and a moldboard angularly secured to said guide member so that the vertical and lateral disposition thereof is determined by the disposition of the upper surface and the side of said road slab, respectively.
